CLAIM

The ornamental design for a decorative vent pattern for circular saw blades, as shown and described.

DESCRIPTION

FIG. 1 is a top plan view of one embodiment of the decorative vent pattern for circular saw blades of the present invention, the bottom plan view being a mirror image of FIG. 1; and,

FIG. 2 is a top plan view of a second embodiment of the decorative vent pattern for circular saw blades of the present invention, the bottom plan view being a mirror image of FIG. 2.

The lines shown in phantom are for illustrative purposes only and form no part of the claimed invention.
